UNITED STATES PATENT OFFICE

2,426,614:

STRETCHING AND DRYING DEVICE

George W. Johnson, Cincinnati, Ohio, assignor
to The American Laundry Machinery Company, Cincinnati, Ohio, a corporation of Ohio

Application January 11, 1946, Serial No. 640,475

7 Claims. (Cl. 223—73)

1

This invention relates to stretching and drying devices, such as are used for sleeveless under-shirts or like articles.

One object of the invention is to provide a simple and inexpensive device of this kind which without adjustment or change will satisfactorily accept and take care of a full range of sizes of garment; which applies the same tension or stretch to each garment, regardless of its size; which has no tendency to distort the garment; and which exposes both surfaces of the entire garment to the effect of the stream of drying air.

Another object is to provide an improved device of this kind which is easy to load and unload, in which the act of introducing the garment into the drying chamber applies the stretching tension, and which is quite compact and highly efficient in operation.

Further objects of the invention in part are obvious and in part will appear more in detail hereinafter.

In the drawings, which represent one suitable embodiment of the invention:

Fig. 1 is a sectional elevation of the complete device on the line 1—1, Fig. 2, and showing the form or garment carrier loaded and in operating position;

Fig. 2 is a sectional plan view on the line 2—2, Fig. 1;

Fig. 3 is a detail sectional elevation on the line 3—3, Fig. 1;

Fig. 4 is a detail elevation, corresponding to Fig. 1, of the garment carrier, showing the parts in retracted position;

Fig. 5 is a similar view, showing the parts of the stretching form expanded, just prior to being advanced into the drying chamber;

Fig. 6 shows the same parts moved into the drying chamber, as in Fig. 1;

Fig. 7 is a plan view of the garment supporting parts, in retracted position; and

Fig. 8 shows the same parts, in expanded position.

Referring to Fig. 1, the device shown in the drawings is in the form of an upright cabinet, designed to rest upon the floor, and including a frame housing or casing 10, which may be round, square, or of any other shape, in plan view, but is shown in Fig. 2 as somewhat wedge shape, provided with a lower heating chamber 11 and an upper drying chamber 12 separated by a horizontal wall 13 having a central round opening 14. The bottom of the heating chamber is open at 15 to permit the flow of air to the inlet of a fan or blower 16, usually operated by an electric

motor (not shown), which blower moves an air stream across suitable heating means, such as the steam coils 17 communicating with supply and discharge pipes 18, 19. The heated air stream thus provided is blown, through opening 14, into chamber 12, in which it travels through and along the garment to be dried, being discharged at the top outlet opening 20.

The drying chamber housing is provided with a hinged front door 21 and within its chamber supports a curved deflector plate 22 for deflecting a portion of the air stream down over the thicker upper strap or shoulder portions of the garment to assist in drying them.

Directly below the door opening is located a vertical plate 23, of the same width as the door, and which serves as a closure for the lower part of the opening through which the garment supporting and stretching mechanism is advanced into the drying chamber or retracted therefrom. This plate 23 supports a pair of grooved rollers 24 which travel on suitable tracks or guides 25. Also mounted on the door within chamber 12, is a rod 26 carrying a traveler or support 27 which is sleeved and slides on a stationary guide bar 28. Fitted to slide on bar 28 is a carriage 29, provided with a traveler 30, somewhat like traveler 27, and which also slides on guide bar 28.

Secured to the front end of carriage 29 is a pull rod 31 extending through an opening in door 23 and provided on its outer end with a handle or knob 32. The purpose of this rod and knob is to enable the stretching mechanism to be expanded and contracted and also advanced into the drying chamber or be retracted therefrom.

The garment stretching and supporting mechanism includes two or more parts, movable relatively to each other for stretching purposes, and so arranged as to enable the garment, in stretched condition, to be supported in the drying chamber, subject to the drying effect of the air stream therein. This is accomplished, in the arrangement shown, by the use of one relatively stationary part, mounted on the door 23, and two other movable parts, mounted on carriage 29.

The stationary part includes two spaced, parallel, upright tubes, posts, rods or bars 33 supported at their lower ends on brackets 34 mounted on door 23, and at their ends having arms 35 extending rearwardly and downwardly and connected by a horizontal cross bar 36, which is adapted to receive, support and hold the shoulder strap portions 37 of the garment 38 shown, as in Figs. 1 and 4 to 8.

The movable part includes two generally similar

loop or inverted U-form post members 39, 40 made of strong wire or rod and suitably secured at their lower ends, as by welding or brazing, to carriage 29. The cross bars 41, at the bends of the U's, usually are inclined, as shown, although that is not essential. The four rod arms of these two members, lie in the same vertical fore and aft plane, midway between rods 33, as shown in Fig. 7. The rods 33 and the rear arms 42 of members 39, 40 are all vertical and parallel, to properly form and shape the garment, while the front arms 43 of said members are inclined, to ease dressing of the shirt on the form.

The operation is as follows:

In the operation of unloading the device, the door is opened, and the knob 32 is grasped and the stretching mechanism is withdrawn from the drying chamber. When the stretching mechanism is thus retracted, as shown in Fig. 4, it is entirely outside of the drying chamber wall, and the rear arm 42 of stretching member 39 is slightly in advance of a plane through the vertical rods 33, giving sufficient room to permit the front portion of an undershirt to be inserted at the top and drawn down between the stationary and movable stretching members. The rear arm 42 of stretching member 40 is slightly in advance of and directly beneath the cross arm 36, so that the back portion of the undershirt, as it is drawn over the form, will lie to the rear of member 40.

An undershirt to be dried thus is drawn down over the stretching members until it assumes the position indicated by the dot-dash lines in Fig. 4, with the stationary member supporting the undershirt by the draping of the shoulder straps over the cross bar 36.

The operator now pushes in on the knob 32 and rod 31, which first moves the carriage 29 rearwardly along rod 26, carrying the stretching arms 39, 40 with it. Members 39, 40 are maintained in their vertical positions by the eccentricity of rod 31 with respect to the center of rod 26. The weight of the stretching mechanism is sufficient to hold the carriage in its withdrawn position, but as it is pushed in, resistance to stretching increases until the shirt is fully stretched as in Fig. 8, by the relative motion between the carriage, with its arms 39, 40, and the stationary rods 33. Thereupon further pressure on knob 32 causes the carriage 29 and the stretching and other parts carried thereby, and including also guide bar 26, door 23, and rods 33, to advance as a unit, the garment sliding into the cabinet with no further stretching, until the parts reach the positions shown in Figs. 1 and 6, door 23 abutting the casing to stop further movement of said door.

The stretching of the undershirt is accomplished by the engagement of the vertical arm 42 of member 39 with the mid portion of the front of the undershirt and the engagement of the vertical arm 42 of the member 40 with the mid portion of the back of the shirt. Thus those members, by their motion, stretch the garment against the resistance of the rods 33. In a similar manner the stretching of the shoulder strap portion at the upper end of the garment is accomplished by the movement of the upper ends of the members 39, 40 against the resistance of the cross bar 36. Thus the entire garment is stretched uniformly throughout.

With the garment introduced into the drying chamber in the manner described, the door 21 is closed. Assuming the fan in operation, or that it is started, and with heat in the coils 17, a

stream of drying air enters the drying chamber and flows up along the garment, both inside and outside thereof, with most of the stream deflected downwardly and returned to the thicker shoulder strap portions, the moisture-laden stream emerging through opening 20. Thus the garment is quickly and thoroughly dried while held in properly stretched position. When the garment is dry, door 21 is opened and the rod 31 is pulled out, which not only withdraws the carriage and the several stretching members 33, 39, 40 from the drying chamber, but also releases the tension or stretch on the garment, enabling it to be readily pulled off from the upper ends of the stretching supports.

It will be readily observed that the amount of movement of the stretching mechanism is determined entirely by the size of the garment placed thereon. At the same time either very small or very large undershirts, or any intermediate size, can be placed upon and stretched by the same stretching mechanism, and by the performance of like operations, without any variations.

When the mechanism is within the cabinet, plate 23 closes the lower portion of the opening, so that the full effect of the hot air stream is secured.

The mechanism described is of simple form, is capable of convenient operation, is highly efficient, and produces a properly dried shirt without distortion of any part, all at minimum cost.

Further objects of the invention in part are obvious and in part will appear more in detail hereinafter.

What I claim is:

1. A shirt stretching device, comprising two supporting members mounted for relative horizontal movement, one thereof being provided with a pair of vertical posts spaced apart laterally and connected together at their upper ends, the other carrying two upright members lying in a plane between said posts and spaced apart fore and aft, and means for relatively moving said supporting members along said plane.

2. A shirt stretching device, comprising two supporting members mounted for relative horizontal movement, one thereof being provided with a pair of vertical posts spaced apart laterally and connected together at their upper ends, the other carrying two upright members lying in a plane between said posts and spaced apart fore and aft, and means for relatively moving said supporting members along said plane, each of said upright members being of inverted loop form.

3. A shirt stretching device, comprising two supporting members mounted for relative horizontal movement, one thereof being provided with a pair of vertical posts spaced apart laterally and connected together at their upper ends, the other carrying two upright members lying in a plane between said posts and spaced apart fore and aft, and means for relatively moving said supporting members along said plane, each of said upright members being of inverted loop form and terminating at its upper end below the upper ends of said posts.

4. Stretching apparatus of the character described, comprising two supports mounted for relative horizontal movement, one thereof being provided with a pair of posts spaced laterally and the other with a pair of posts spaced apart fore and aft, all of said posts being parallel to each other and extending upwardly from the supports in a direction normal to the direction of their

relative horizontal movement, and means whereby said supports may be relatively moved in the fore and aft direction to horizontally stretch an article supported upon said posts.

5. Stretching apparatus of the character described, comprising two supports mounted for relative horizontal movement, one thereof being provided with a pair of posts spaced laterally and the other with a pair of posts spaced apart fore and aft, a bridge member cross-connecting the upper end portions of the posts of one pair, and means whereby said supports may be relatively moved in the fore and aft direction to stretch an article supported upon said posts and bridge member.

6. Stretching apparatus of the character described, comprising two supports mounted for relative horizontal movement, one thereof being provided with a pair of posts spaced laterally and the other with a pair of posts spaced apart fore and aft, a bridge member cross-connecting the upper end portions of the posts of one pair and lying at a level above the upper ends of the posts of the other pair, and means whereby said supports may be relatively moved in the fore and aft direction to stretch an article supported upon said posts and bridge member.

7. Stretching apparatus of the character described, comprising two supports mounted for

relative horizontal movement, one thereof being provided with a pair of posts spaced laterally and the other with a pair of posts spaced apart fore and aft, a laterally extending bridge member cross-connecting the upper end portions of the posts of the first named pair, and means whereby said supports may be relatively moved in the fore and aft direction to stretch an article supported upon said posts and bridge member.
